(57) **CLAIM**

The ornamental design for a combined speaker and microphone as shown and described.

DESCRIPTION

FIG. 1 is a perspective view of a combined speaker and microphone showing the new design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a partial enlarged view of FIG. 1 thereof;

FIG. 10 is a partial enlarged view of FIG. 1 thereof; and,

FIG. 11 is a partial enlarged view of FIG. 2 thereof.

The dot dash broken lines encircling portions of the combined speaker and microphone in FIGS. 1 and 2, and, illustrated in the enlarged views of FIGS. 9, 10, and 11, form no part of the claimed design.

1 Claim, 11 Drawing Sheets(56)
